Inventor:

F. E. Stevenson.

By his attorneys,
Baldwin & Wright

UNITED STATES PATENT OFFICE.

FRANCIS E. STEVENSON, OF MOUNT GILEAD, OHIO, ASSIGNOR TO THE HYDRAULIC PRESS MANUFACTURING COMPANY, OF MOUNT GILEAD, OHIO.

PRESS.

Application filed June 6, 1921. Serial No. 475,247.

To all whom it may concern:

Be it known that I, FRANCIS E. STEVENSON, a citizen of the United States, residing in Mount Gilead, county of Morrow, and 5 State of Ohio, have invented certain new and useful Improvements in Presses, of which the following is a specification.

This invention relates to presses, especially intended for household use and which are 10 employed for expressing juices from apples and other fruit and for similar purposes, and the object of this invention is to provide a press of simple construction and few parts, but which is strong and durable, easily operated and conveniently taken apart, cleaned and re-assembled.

According to my invention the press is associated with a grinder which prepares the fruit for the pressing operation and delivers 20 the ground material to bags which, when sufficiently filled, are placed between grooved disks supported in a saucer which is connected by strain rods with a crosshead supporting the grinder and also supporting a 25 screw which operates on a shoe bearing on the topmost disk. When the press is operated by the screw the juices flow into the saucer which is provided with a spout delivering to a suitable receptacle.

30 In the accompanying drawings,

Figure 1 is a front view of a combined grinder and press embodying my improvements attached to a supporting table;

Figure 2 is a side view thereof;

35 Figure 3 is a view, partly in section and partly in side elevation, of the press;

Figure 4 is a view in section of the grinding mechanism, showing how it is associated with the screw press and how it delivers to a 40 bag;

Figure 5 is a bottom plan of the cross head and part of the grinder;

Figure 6 shows a section on the line 6-6 of Fig. 5;

45 Figure 7 shows an elevation of the rotary cutter forming part of the grinding mechanism;

Figure 8 shows an elevation of the partition employed in the grinder.

50 The press comprises a saucer A, having a delivery spout a, strain rods B and a cross-head C, rigidly attached to the upper ends of the strain rods. A press screw D extends

centrally through the cross-head and is provided with operating handles d.

55

A grinder E is supported by the cross-head, its body portion being preferably integrally formed therewith. Said grinder comprises a hollow body portion e, having a receiving hopper e' and a delivery opening 60 e''. The grinding chamber e³ is formed with ribs e⁴, which cooperate with the screw F in reducing the material to a pulp and said screw carries a cutter G of suitable construction but preferably of the kind 65 illustrated in Fig. 7. The cutter is rigidly secured to the screw and revolves therewith. The screw F is supported at its inner end in a partition H having openings h through it and held in place by a set screw h' engaging 70 a notch h² (Fig. 8) in the partition. The partition bears against a shoulder h³ in the body of the grinder and is pressed against said shoulder by the screw. Said screw is formed at its outer end with an axle or trunnion f, which extends through a screw plug f', which closes the outer end of the grinding 75 chamber. The axle carries an operating handle F'.

When material is fed to the grinding 80 chamber it is partially reduced to pulp by the screw cooperating with the ribs e⁴ and is fed towards the discharge opening of the grinder. Before reaching said discharge opening, however, the material is operated 85 upon by the cutter which further reduces it.

By the construction shown, the screw and cutter with the partition may be readily removed from the grinding chamber, cleaned and as readily replaced.

90

Hooks or pins K on the bottom of the grinder are adapted to support bags L of suitable material which receive the ground material. When the bags are sufficiently filled they are placed in the press and the 95 screw D is operated to express the juice. The bags are placed between grooved disks M, N, O, (Fig. 3). The lower disk M rests on the saucer A and is grooved on its upper side. The disk N is grooved on both sides, 100 while the disk O is grooved on its under side.

In the drawings I have shown two bags L and three grooved disks, but of course this number may be varied. When the bags and disks are arranged as shown in Fig. 3, the 105 screw D is operated and the juices are

pressed through the bags and flow into the saucer A, from which they are discharged through the spout *a* into a suitable receptacle R. The screw D bears upon a metal shoe *o*, 5 carried by the disk O.

Any suitable means may be employed for supporting the combined press and grinder. The drawings show the press supported on a 10 table T and attached thereto by clamping devices U of well-known construction.

A combined grinder and press of the kind herein illustrated and above described is of simple construction, may be furnished at comparatively low cost, is easily operated 15 and conveniently kept in proper working condition. It may be employed for making cider, grape-juice and other fruit juices for jellies, etc. If desired, the grinder may be

used alone for some purposes, such as making sausage, ground meat and the like and 20 the press may be used separately in various ways.

I claim as my invention:

A combined press and grinder comprising a saucer, a cross head, connections therebetween, a press element carried by said cross-head, a grinder having a body portion formed integral with the cross head and having a discharge opening above the saucer, and means carried by the cross head and grinder 25 body for suspending a receptacle for ground material therefrom.

In testimony whereof, I have hereunto subscribed my name.

FRANCIS E. STEVENSON.
